CLOTHESLINE HANGER

Phillip B. Cadman, Venice, Calif.

Application August 30, 1949, Serial No. 113,231

5 Claims. (Cl. 211—94)

1

This invention relates to clothes-line hanger apparatus. Its general object is to provide hanger apparatus for a series of stretches of clothes-line, all arranged compactly within a relatively small area, and with overhead support such that a person may walk beneath a clothes line throughout this area without colliding with any of its supports.

A further object is to provide a clothes line hanger apparatus which is adapted to be attached to the side of a garage or other building in a back yard, and which embodies cantilever suspension such as to leave the entire space beneath it unobstructed.

A further object is to provide such a clothes line hanger apparatus which is of relatively simple and inexpensive construction.

Another object is to provide such a hanger apparatus having relatively simple leveling and adjusting means.

Other objects will become apparent in the ensuing specification and appended drawings in which:

Fig. 1 is a plan view of a hanger apparatus embodying my invention, attached to a garage;

Fig. 2 is an elevational sectional view of the garage, showing one of the hangers attached thereto, taken on the line 2—2 of Fig. 1;

Fig. 3 is an end view of the hanger of Fig. 2;

Fig. 4 is a detail sectional view of a hanger beam with extension;

Fig. 5 is a detail view of a beam without extension;

Fig. 6 is a detail sectional view taken on the line 6—6 of Fig. 5;

Fig. 7 is a detail sectional view of a line connector; and

Fig. 8 is a sectional view of a modified form of the line connector.

My improved clothes-line hanger embodies a pair of hanger beams 11 each carrying a plurality of bands 12 which have eyes 13 through which clothesline rope or cable 14 may be threaded. The inner ends of beams 11 are loosely receivable in sockets 15 which in turn are attachable to studs 16 of a garage or other building.

The beams 11 are supported by braces 17 each adapted to be attached at one end to a stud 16 of the building and attached at its other end to a beam 11. Each beam 11 is fabricated from metal pipe and its end may be threaded into one end of a union 21 (Fig. 4) or an end cap 20 (Fig. 5). Into the other end of each union 21 is threaded a short extension 22, the outer end

2

of which is finished with a cap 23 threaded thereon.

Braces 17 are secured to studs 16 by means of screw eyes 24. Each brace 17 passes through a screw eye 24 and the latter is screwed into the stud 16. Each brace 17 has a turnbuckle 25 which is utilized to adjust the length of the brace in order to level the beam 11. Each brace has at its outer end a hook 26 which is engaged in the end of a slot 27 (Fig. 5) in the outer end of beam 11, and secured by the abutting engagement of union 21 (or cap 20).

Lateral braces 28 extend diagonally from the outer ends of beams 11 to the corners of the building in the plane of beams 11. Each brace 28 has at its outer end a hook 26 engaged in a slot 23 in the outer end of a beam 11 and its inner end is anchored to a corner stud 16' by means of a screw eye 30.

Braces 17 are inclined upwardly in substantially a common plane which is roughly parallel to the plane of roof 31, whereby to provide a cantilever arrangement for supporting the downward pull of the loaded clothes-line upon beams 11, while the lateral braces 28 provide lateral support for taking the horizontal inward pull against beams 11, developed by the loading of lines 14. The downward load upon beams 11 develops therein a compressive force which pushes the inner ends of beams 11 into sockets 15, maintaining the connections between these parts. Thus it becomes possible to employ loosely-socketed connections between beams 11 and sockets 15, eliminating the expense of threading these connections.

The braces 17, in addition to their bracing function, have the additional function of serving as slide rails for a series of rings 32 which are secured to the side edges of a tarpaulin awning

40 33. The awning 33 provides a rainshed cover for the central portion of the area traversed by lines 14. An operating line 34, secured at its lower end to a rod 35 binding the forward edge of awning 33, passes around a pulley 36 which is mounted at the upper extremity of garage wall 37, and thence passes downwardly to provide a depending portion that may be grasped and pulled so as to slide the awning to the retracted position shown in Figs. 1 and 2. The upper end of the awning 33 may be attached to the garage beneath roof 31 as indicated at 38.

Eyes 13 are connected to collars 12 by means of threaded shanks 39 (Fig. 7). The threaded shanks 39 function as set screws and the eyes 13 function as wing heads for setting the shanks

39 against beams 11 to fasten collars 12 in selected positions. Thus provision is made for adjustment of collars 12 to any desired spacing along beams 11.

Fig. 8 illustrates a modified form of the line connector, which can be used in lieu of that shown in Fig. 7. An eyebolt 13a has its threaded shank passed freely through an opening in collar 12a, and threaded through a nut 39', which bears against the inner wall of collar 12a. The shank bears against beam 11 to lock the collar thereto.

Each brace 28 incorporates a turnbuckle 25 for tightening the lines 13 whenever they tend to sag.

Where extension 22 is employed, a dowel 40 is inserted into the abutting ends of the insert and the beam 11, rigidifying and bracing the connection between the beam and the extension.

I claim:

1. In a clothesline hanger, a pair of laterally spaced, parallel tubular beams each having, at an inner end, means for attaching the same to a vertical wall of a building and each having, at its outer end, male screw threads and a pair of slots disposed respectively at the outer and upper sides thereof; cantilever brace rods comprising a hanger rod and a lateral bracing rod for each beam, each rod having at its outer end, a hook extending through a respective one of said slots and hooked into the respective beam at the bottoms of said slots; and an internally threaded fitting threaded upon said male threads and engaging said hooks to lock them in said slots; and means for attaching to said beams, a clothesline extending back and forth between said beams in transverse stretches.

2. A hanger as defined in claim 1, wherein said fitting consists in an end cap.

3. A hanger as defined in claim 1, wherein said fitting comprises a nipple; and including an extension member having a threaded end secured in said nipple and thereby attached to a respective beam in alignment therewith.

4. In a clothes line hanger, a pair of laterally spaced, parallel horizontal tubular beams each having, at an inner end, means for attaching the same to a vertical wall of a building and each having, at its outer end, means defining a pair of adjacent slots therein; a cantilever hanger rod for each beam disposed generally in a vertical

plane above its respective beam, and a cantilever lateral bracing rod for each beam, disposed in generally the same plane as the beams, each of said rods having at its outer end a hook extending through a respective one of said slots and thereby hooked into the respective beam; and means for attaching to said beams a clothes line extending back and forth between said beams in transverse stretches.

5. In a clothes line hanger, a pair of laterally spaced, parallel hanger beams each having, at one end, means for attaching the same to a vertical wall of a building; two sets of collars through which the respective beams extend; each 10 collar having an internal diameter greater than the external diameter of the respective beam; each collar having a radial opening at one side thereof; a set screw having a threaded shank portion extending through said opening; a nut 15 threaded onto said threaded shank, said collar being disposed eccentrically with reference to said beam, and defining therewith, on the side adjacent said radial opening, a space in which said nut is received and interposed between the inner face of said collar and the outer face of said beam, said shank extending through said nut and bearing against said beam to lock the collar to the beam; said set screw having a wing head in the form of an eye, said eye functioning as 20 line support through which a clothes line may be threaded for attaching the same to said beam.

PHILLIP B. CADMAN.
